PRINTING TELEGRAPH RECEIVER

Max Amann, Alfred Lahl, and Hans Hatzinger,
Frankfort-on-the-Main, GermanyApplication February 29, 1936, Serial No. 66,426
In Germany March 2, 1935

17 Claims. (Cl. 178—34)

This invention relates to printing telegraph receivers having a type wheel and a selecting mechanism which comprises a set of rotary permutation or code discs and a set of testing members 5 adapted to cooperate with the discs and which can be set into different positions by means of a single magnet. In this type of receiver, the various testing members are successively set by the magnet under the influence of the successive 10 current impulses of a received telegraph signal through the agency of a rotating device. The whole set of testing members is then moved towards the rotating discs which have grooves in their peripheries arranged so that the testing 15 members can only engage in them and thus lock the discs in one particular angular position of the discs for any one setting of the testing members. The type wheel is connected to the code discs and rotates with them. When the discs are 20 at rest, a particular type lies in front of a printing hammer by means of which this type can be printed.

The object of the invention is to reduce as far as possible the load borne by the above-mentioned 25 magnet when setting the testing members and to transmit the force to be used for setting these testing members through an auxiliary device so that the sensitivity of the magnet can be increased and the magnet can be made to respond to weak 30 current impulses. In accordance with the invention the setting of the testing members is effected as a consequence of the position taken up by a rotary device controlled by the magnet and as a result of the force maintaining this device in rotation. The rotary device is positively set during the rotation so as to determine a particular 35 setting of the testing members and is held in the set position merely by bringing the armature of the magnet into one of its two extreme positions at particular intervals of time. The testing 40 members are thus set only indirectly in dependence upon the position of the armature. The magnet itself thus does not exert the force for setting the rotary device and for setting the testing members. The position of the magnet armature is moreover positively determined by the 45 rotary device and the setting of the testing members is effected positively according to the position assumed by the rotary device which is itself dependent upon the position of the armature, by the force maintaining the device in rotation.

In order that the invention may be thoroughly 50 understood and be more readily carried into effect, an example of construction in accordance

therewith will now be described with reference to the accompanying drawings, in which:—

Figure 1 is a plan view of a telegraph receiver in accordance with the invention.

Figure 2 is a sectional elevation of the receiver. 5

Figure 3 is a cross-section taken on the line III—III in Figure 1.

Figures 4—6 illustrate details of the mechanism shown in Figure 3. 10

Figure 7 is a cross-section taken on the line VII—VII in Figure 1.

Figure 8 is a diagrammatic representation of the selecting mechanism.

Figures 9 and 10 show the selecting mechanism 15 in two testing positions.

Figure 11 is a perspective view of the testing levers of the selecting mechanism.

Figure 12 shows diagrammatically the positions taken up by various parts of the selecting mechanism 20 on selection of the letter A.

Figure 13 is a cross-section taken on the line XIII—XIII in Figure 1.

Figure 14 is a sectional plan view of part of the arrangement shown in Figure 2. 25

Figures 15 and 17 are plan views showing in two different working positions the device provided for bringing the printing mechanism into operation.

Figures 16 and 18 are respectively a side elevation and a front elevation of part of the device shown in Figures 15 and 17, and 30

Figure 19 is a sectional elevation to a larger scale of a detail illustrated in Figures 15 and 17.

The illustrated receiver has a single receiving 35 magnet and the whole of the members which are necessary for printing a type are mechanically controlled during and after reception of the appropriate code signal.

The type is carried by a type wheel and the 40 printing takes place on a paper strip when the type wheel is at rest. The type wheel can assume 64 different positions and one of 32 different positions can be selected on reception of a 5-unit code signal. Shift signals cause the type wheel 45 to be stepped backwards or forwards through 1/64th part of a revolution. In this way, figures and signs can be printed in addition to letters of the alphabet. In some positions, corresponding to switching steps and the like, printing is 50 prevented.

The setting of the type wheel is controlled by means of a selecting mechanism comprising two sets A and B each of 5 testing levers each of which cooperates with a pair of code discs. The testing 55

levers can be displaced individually relatively to the pair of code discs associated with them. This displacement is effected by means of a distributor arm which is rotated as synchronously as possible with the transmitting distributor or the received signals. The various testing levers are displaced successively and the displacement is controlled indirectly by the receiving magnet in accordance with the received code signal. When 10 the testing levers have been set in their displaced positions, they are brought, as a set, into contact with the pair of code discs associated with them, so that they can engage, as a set, in the grooves formed in these discs when the latter are subsequently rotated. This engagement of the testing 15 levers in the grooves in the code discs is only possible in one of 32 positions of the code discs, this position being determined by the setting of the testing levers. The type wheel rotates with 20 the code discs and thus takes up the position determined by the selecting mechanism and in which the code discs and the type wheel are stopped by the testing levers when the latter come into the grooves in the code discs. The 25 printing or other operation then takes place with the type wheel at rest. The selection of the position of the type wheel corresponding to the setting of one set of testing levers can take place while the other set of testing levers is being set 30 by a subsequent signal.

The printing of the selected type (or the shift or other step) is effected directly by the printing mechanism after the code discs and the type wheel have been brought to rest. These steps are 35 effected by a motor.

The receiver (Figure 1) is driven by a motor 162 through a worm and a worm wheel 104, 105. This single motor is also used to drive and control the distributor arm 152 (and the parts connected therewith), to rotate the code discs 193- 40 196 and the hub 126 which carries the type wheel 125 and to control the parts connected with the printing or with the prevention of printing.

The worm 104 is connected to the shaft 107 of 45 the receiver through a flexible coupling 108. The shaft 107 carries two toothed wheels 112, 113. The wheel 112 meshes with a wheel 114 of twice its own diameter and forming part of the start-stop mechanism. The wheel 113 meshes with a 50 smaller wheel 115 which drives the selecting mechanism. The wheel 114 is fixed to the shaft 118 of the receiver by means of a hub 116 forming one part of a dog clutch (Fig. 2) and a grub screw 117.

55 The wheel 115 (Fig. 2) is mounted to rotate on the type wheel shaft 122 which is coaxial with the shaft 118. The type wheel 125 and the cam discs 127 associated with it are mounted on the carrier member 126 keyed to the front end of the shaft 122.

At its front end, the shaft 107 has fixed to it one part 262 of a dog clutch (Figures 15 and 17) by means of which the parts which come into play for effecting printing are coupled.

60 Two sleeves 128 and 129 (Figs. 2 and 14) are freely mounted on the continuously rotating shaft 118 of the receiver. The sleeve 128 has forked lugs 192 (Fig. 2) projecting from it in which engage dogs 191 on the part 130 of the 65 clutch 130, 116, which part is free to slide on the sleeve 128. A helical spring 132 abuts against the lugs 192 and the part 130 and is housed within a drum 131 rigidly fixed to the part 130. This spring 132 tends to cause the clutch 130, 116 to engage but is prevented from so doing in the 70

normal position illustrated in Fig. 2 by the pawl 133, seen in Figs. 3 and 4.

The sleeve 128 has oblique grooves 134 (Fig. 14) cut in it at one of its ends in which engage dogs or lugs 135 projecting radially inwards from a ring 136, fixed to a sleeve 137. This sleeve 137 is capable of axial displacement and is guided during such displacement by guide slots 138 in the sleeve 129. A drum 153 to which is fixed the distributor arm 152 is mounted on the sleeve 129. This drum can be reciprocated easily along the sleeve 129 without angular displacements and, for this purpose is provided with pins 154 (Fig. 2) ending in rollers which lie in the grooves 133 formed in the sleeve 129.

The sleeve 129 terminates at its forward end in a flange 159 to which are fixed a cam disc 160 and a wheel 162.

Rotation of the sleeves 128 and 129 with the shaft 118 which always takes place to the extent 20 of half a revolution is effected by the pawl 133, (Figs. 3 and 4).

The pawl 133 is pivotally mounted at 173 and its curved end normally projects into one of two diametrically opposite openings 171 in the drum 25 131 and holds the drum in the stop position. In this position, an oblique surface 188 bounding the opening 171 bears against an oblique surface at the upper left hand end of the pawl 133 so that the clutch 116, 130 (Fig. 2) is held disengaged. 30

The drum 131 is prevented from rotating backwards by the check pawl 177 (Figs. 3 and 5) pivoted at 178 and which normally abuts against the upper edge of the opening 171 opposite to that in which the pawl 133 is engaged.

A spring 176 urges the pawl 177 into engagement and tends to hold the pawl 133 out of engagement with the openings 171 in the drum 131.

In the normal position, the spring 176 is prevented from swinging the pawl 133 clockwise 40 because the lower end of the arm 175 attached to the pawl abuts against the cranked end of a bar 185 forming part of a pivotable member 183, (Fig. 6).

A third arm 174 (Fig. 3) moving with the pawl 45 133 is disposed in the plane of two diametrically opposite abutments 179 formed on the edge of the drum 131. The arm 174 can only come into contact with the abutments 179 when the pawl 133 is pivoted out of the normal position. This only happens shortly before the completion of the half revolution of the drum 131. The bar 185 can be pivoted about the pivot 183a against the action of a weak spring 184. The arm 182 of the pivoted lever 183 lies opposite the end 55 181 of the armature 148 of the magnet 150 (Figs. 3, 6 and 7).

When the armature 148 drops, its end 181 abuts against the arm 182, pivots the lever 183 against the action of a spring 184 and releases the arm 60 175. The pawl 133 is now effectively acted on by the strong spring 176 and, as a result, the arm 175 rides over the sloping face 186 (Fig. 6) of the cranked part of the bar 185. The force thus exerted on the arm 185 assists in the pivoting of 65 the lever 183 and the pawl 133 is thus effectively unlatched by a small movement of the armature 148.

In the normal position, the magnet coils are supplied with current and hold the armature 148 70 in the position illustrated in Fig. 7 against the action of the spring 187.

The disengagement of the pawl 133 from the opening 171 in the drum 131 when the armature 148 drops allows the compression spring 75

(32, (Fig. 2) to bring the teeth on the clutch member 130 into engagement with the teeth on the rotating clutch member 116. From this instant onwards, the shaft 118 is coupled by the dogs 191 5 to the sleeves 128 and 129 and the whole of the parts guided by the sleeves, including the distributor arm 152, are rotated together.

Shortly before the drum 131 has completed half a revolution, one of the abutments 179 (Fig. 10) abuts against the arm 174 and turns the pawl 133 against the action of the spring 176. At this instant, the opening 171 in which the pawl 177 15 was previously engaged is opposite the pawl 133. The sloping surface 188 bounding this opening now abuts against the head of the pawl 133 and the drum 131 is moved in the direction of the arrow shown in Figure 4. This causes the clutch 130, 116 to be disengaged, the drum 131 to be stopped and the arrangement to be brought to 20 rest after exactly half a revolution.

The selecting mechanism comprises two sets A and B of testing levers 158 and the code discs 193—196. (Figs. 8—12). The testing levers 158 are not shown in Fig. 2.

25 Each testing lever 158 is mounted on a pin or shaft 198 (Fig. 11). The latter are mounted so as to be movable axially in the brackets 121 and the side plates 201, (Figs. 1 and 11). The side plate 201 for each set of levers is held at the correct distance from the bracket 121 by a distance piece 202. The pins or shafts 198 and therefore the testing levers on them can be set into a forward or a backward position by means of control levers 157 (Figs. 1 and 13) which project through slots in the flat ends 199 of the shafts 198. They are maintained in these positions by springs 200 (Fig. 11).

The testing levers 158 can be displaced parallel to the axis of the code discs, the levers 158I—V 40 of the set A relatively to the code discs 193, 194 and the levers 158I'—V' of the set B relatively to the discs 195, 196. This is diagrammatically illustrated in Figure 8. The distance apart of the code discs in a pair is less than the sum of the 45 thicknesses of two testing levers 158, (Fig. 11). The tails 204 of the testing levers of each set abut against each other and are connected together by a spring 207 or 207'. The displacement of the testing levers parallel to the axis of the code discs 50 does not bring their tails 204 out of contact with each other. This is clear from Figure 11, where the testing lever 158III is shown in the extreme right hand position and the testing lever 158IV in the extreme left hand position.

55 This mutual support of the testing levers 158 prevents independent movement of the levers about their shafts 198.

The topmost lever of the set B and the lowermost testing lever of the set A each has a rearward extension 205 and the topmost lever of the set A and the lowermost lever of the set B a similar extension 205' (Figs. 9 and 10). A spring 206 is anchored at one end to the projection 205 of the lever 158V and at the other to a control lever 60 167; a spring 206' is similarly connected to the lever 158V' and the control lever 168. The ends 405 and 405' of the control levers 167 and 168 abut against the projections 205' so that when one of these levers is swung about its pivot 167' or 65 168', the set of testing levers 158 associated with it is swung as a whole about their pivotal axes into or out of engagement as the case may be with the pair of code discs associated with that set.

75 The lowermost testing levers 158V and 158I'

of the two sets A and B have projections 208 and 208' which control an escapement for the printing mechanism.

The levers 157 (Fig. 13) by means of which the testing levers 158 are displaced are pivotally 5 mounted in bearings 236 on the rear side of the frame 121. The levers 157 are curved at their free ends and end in lugs 237 disposed in a circular path wiped over by the lug 156 of the distributor arm 152 (Figs. 1, 2 and 7). The lugs 237 10 have sloping surfaces and when the lug 156 passes over them, the free ends of their levers 157 are depressed.

The distributor arm 152 is fixed to the drum 153 (Fig. 2) which is free to move axially relatively to the sleeve 129 but is constrained to rotate with the latter by the pins 154. The arm 152 and the drum 153 are acted on by a compression spring 155 which abuts against the flange 159 of the sleeve 129. The drum 153 in the right 20 hand position illustrated in Figure 2 reaches almost to the base of the drum 141.

The drum 141 is fixed on the supporting frame 145. 10 slowly rising and suddenly falling cams 149 (Fig. 7) are distributed over its circumference. During half a revolution of the sleeve 129, these cams, by coming into contact with the two rearwardly projecting lugs 151 (Fig. 2) on the distributor arm 152 determine five forward and backward movements of the latter. The two 30 lugs 151 ride at the same time, over oppositely disposed cams 149, the latter being arranged symmetrically on the drum 141.

The cranked end 147 of the armature 148 of the magnet 150 projects through an opening 146 35 formed in the lower part of the drum 141 (Figs. 2 and 7). It prevents the drum 153 from being moved by the spring 155, as, while the lugs 151 are sliding over the cams 149, it slips between the edge of the drum 153 and the base of the drum 40 141 and remains here when the lugs 151 have passed clear of the cams 149.

The lever 147 is yieldingly connected to the armature 148 by means of a spring 199 (Fig. 7). This armature is periodically brought up to the 45 pole 165 by the action of the cam disc 160 on the member 164 fixed to the armature. The magnet 150 therefore only has to exert a magnetic force to hold the armature 148 attracted to the pole when the part 164 is free of the cams 163. 50 This release of the part 164 by the cam 163 always takes place at about the middle third of each signal impulse, at which instant, the signal current has reached its peak value. If this release takes place when no current is flowing, the armature 148 is turned anticlockwise by the spring 55 187 and the lever 147 comes out of contact with the drum 153.

The cam disc 160 is fixed to the sleeve 129 which also moves with the distributor arm 152 60 and the drum 153. The arrangement is so devised that the distributor arm 152 and the drum 153 are engaged by a cam 148 before the part 164 is engaged by a cam 163 and are released by the cam 149 at the earliest, at the same instant as the armature projection 164 is released by the cam 163. In this way, the engagement of the armature lever 147 between the drum 153 and the stationary drum 141 is ensured. In order to synchronize the signal impulses and the rotation of the cam disc 160, the five successive cams 163 are advantageously made of increasing 65 length.

The distributor arm 152 and the drum 153 can only be moved axially by the spring 155 when 75

the lugs 151 lie between two of the cams 149 on the drum 141. When the magnet 150 is energized, such axial movement is prevented by the lever 147 of the armature 148. The lugs 237 on 5 the levers 157 are also disposed in the intervals between the cams 149.

If, then, the drum 153 is prevented from moving by the armature lever 147, the lug 156 on the arm 152 abuts against the lug 237 formed 10 on a lever 157 so that the associated testing lever 158 is transferred into its other extreme position. On the other hand, when the lug 151 of the arm 152 is allowed by the armature lever 147 to engage in the space between two of the cams 149, the lug 156 15 is out of the plane of the lugs 237 on the control levers 157. The latter therefore remain in the extreme forward position.

The extreme forward position of the levers 157 and the testing levers 158 is determined by a 20 cam 238 (Figs. 1 and 13) before these levers are set by the lug 156 of the arm 152. This cam 238 is arranged on the disc 162 at a given angle α (Fig. 13) in advance of the lug 156 on the arm 152. In this way, shortly before the lug 156 25 wipers over the lugs 237, the testing levers 158 are brought successively into the forward position by engagement of the cam 238 with the rear side of the lugs 237, in which position they can be acted upon by the following lug 156.

30 The levers 167 and 168 (Figs. 9 and 10) which rest on the uppermost testing levers 158I and 158I' are controlled by a cam groove 161 in the wheel 162 and a follower pin 166 (Fig. 9). They are pivoted simultaneously, one inwards the other 35 outwards during the last 7th part of each half revolution of the wheel 162.

When, at the end of the half revolution, the lever 167 (Fig. 9) has been brought into action the member 405 abuts against the free end 205 40 of the uppermost testing lever 158I of the set A. The blow is transmitted through the tails 204 to the lever 158V so that all the levers of the set A are swung clockwise about their bearing pins 198. Their ends 203 are thus removed from the 45 grooves in the code discs 193, 194. At the same time, the lever 168 is swung so that its member 405' is removed away from the projection 205' of the lowermost lever 158I' of the set B. The spring 206' pulls on the lever 158V' and all 50 the levers of the set B are swung counterclockwise. The ends 203 of these testing levers now lie on a pair of code discs 195, 196 but do not immediately engage in the grooves therein. (It cannot be assumed that out of the many cases 55 that can occur, that case will be present in which the whole of the five testing levers will be opposite corresponding grooves in the discs and, therefore, be able to engage immediately therein.) Moreover, the testing levers of the set B remain 60 under the influence of the spring 206' until all the testing levers can engage simultaneously and stop the code discs.

65 The code discs 193—196 are rigidly connected to the flange 209 (Fig. 2) on the shaft 122. The pair of code discs 193, 194 belonging to the set A is identical with the pair of discs 195, 196 belonging to the set B, but the two pairs are displaced through 180° relatively to each other. The discs in each pair are also similar except 70 that one is provided with cams in the form of humps and the other with cams in the form of grooves.

75 The smallest cam in the code discs extends over $\frac{1}{2}$ part of its circumference. The distance between the ends 203 of the testing levers 158

in each set has a corresponding value. The ends 203 of all the testing levers of both sets are exactly the same.

The flange 209 can, if desired, be provided with a tooth in which can engage a check pawl for 5 preventing recoil of the code discs when they are stopped by the testing levers. Such a pawl could be brought into action by the movement of the control levers 167 and 168.

The toothed wheel 115 (Figs. 1 and 2) is freely 10 mounted on the shaft 122. It is frictionally connected to it both through the clutch plate 210 (Figure 2) and through the outermost code disc 196. The pressure exerted on the clutch plate 210 can be varied by displacement of a 15 ring 212 and a resilient, split, dished disc 211. The position of the ring 212 can be adjusted by means of a nut 213 and any setting can be maintained by means of a lock-nut 214.

As already stated, the drum 126 carrying the 20 type wheel 125 is fixed to the type wheel shaft 122 by means of a key 220. The type wheel carries groups of cam discs 127 or a grooved drum for controlling auxiliary devices.

The selecting mechanism operates as follows:— 25

The code signal received in connection with the letter A consists firstly of a no current impulse (start element), then two current impulses, then three no current impulses and finally a 7th current impulse (stop element).

30 On reception of the start impulse, the sleeve 129 is coupled to the shaft 118 for half a revolution. During this rotation the distributor arm 152 is displaced axially five times against the action of the spring 155 by means of the lugs 151 35 which slide over the cams 149, once at the beginning of each of the five received current impulses. At the same time, a cam 163 on the disc 160 acts on the part 164 of the armature and brings the armature 148 up to the pole 165. At about the 40 first third of each current impulse, (with disc 160 also of the stop impulse) the lugs 151 and 164 reach the highest point of the cams.

The arm 152 is pressed back together with the drum 153 by the spring 155 as soon as the end of 45 a cam 149 is reached. If the cranked end of the lever 147 is at this instant lifted and the armature attracted, the drum 153 cannot move backwards and the arm 152 remains in the displaced position in which its lug 156 acts on the lug 237 50 of the appropriate testing lever.

In the case under consideration, after the start impulse, the armature which has been brought near the pole remains attracted for two current 55 impulses and thus prevents the return movement of the arm 152. The lug 156 on the distributor arm thus acts on the lugs 237 of the control levers 157I and 157II (Fig. 13), and thus displaces the testing levers 158I and II. The following three no-current impulses allow the 60 armature which, on further movement towards the pole by means of the cam 163, meets no magnet holding force, to release and, as the lever 147 is also released, the arm 152 and the drum 153 to assume the right hand position illustrated in 65 Figure 2. The three levers 157III, IV and V are thus not effected by the lug 156 and with the testing levers 158III, IV and V, remain unset.

The resetting cam 238 is in advance of the lug 156 of the distributor arm 152 and brings into 70 the forward position the control lever 157 of the set A which is to be acted upon.

After reception of the signal, the testing levers 158I—V of the set A are displaced as is shown in Figure 8 for the set B.

However, during the reception of the stop current impulse, the displaced levers of the set A are released by the lever 167 through the agency of the cam track 161 in the wheel 162. The testing levers are thus pivoted by the spring 206 acting on the end 205 of the lever 158V so that the ends 203 of these levers lie on the code discs 193 and 194 of the set A. The testing levers of the set B which up to now have been in engagement with their code discs are swung out of engagement as a set by the lever 168 which is caused to strike the tail 205' of the lever 158I' (Fig. 10). The levers 158I'—V', however, are still not returned into the forward normal position.

15 In the meantime, on reception of the stop impulse the maintenance of the sleeve 129 is prepared by the arm 152 and can be effected without influencing the succeeding steps.

As soon as the ends 203 of the testing levers 20 in set B are removed from their operative position in the grooves of the discs 195 and 196, all restraint is removed from the code discs and these are driven by the wheel 115 through the clutch 214, 215. The shaft 122 and all the code discs 25 and all the other parts rotate together at a relatively high speed.

The time required for a complete revolution of the shaft 122 corresponds approximately to the duration of five signal impulses on the assumption that two sets of testing levers are used.

During the rotation, all the ends 203 of the engaged set A of testing levers will slide on the code discs 193 and 194. These testing levers can engage in the grooves of these discs when, as illustrated in Figure 12 for the set B, the one appropriate position out of the 32 possible engaging positions is reached. In any other position, there may be from one to four of the levers 158 above corresponding grooves, but no engagement therefore is possible because the abutment of the testing levers one on another only allows the levers to move all together, that is to say, as a set.

The engagement of the levers of the set A is accelerated by the action of the spring 206. 45 When the selecting position is reached, the shaft 122 is suddenly stopped by the ends 203 of the testing levers 158I—V. The impact caused on stoppage of the type wheel shaft 122 is received directly by the bearing pins 198 of the testing levers.

The relative positions assumed by the code discs and testing levers for the selection of the letter A (the case under consideration) is illustrated in Figure 12. Here, however, the selection was effected by the lever of the set B and the discs 195 and 196 of the set B which are displaced by 180° relatively to the code discs of the set A. The letter A on the type wheel 125 is then in the printing position. The two sets A and B 60 are used alternately for successive incoming signals. During one half revolution of the distributor arm 152, the testing levers of the set A are set and are released for cooperation with the discs 193, 194 and during the next half revolution, the levers of the set B are set and released for cooperation with the discs 195, 196.

The impulses transmitted to the magnet 150 from the transmitter are more or less distorted according to the conditions in the line.

70 It is usual, for the purpose of controlling the selecting mechanism, to use only those parts of the various impulses of the signal in which the most favourable current values occur. As the point at which the most favourable operating conditions occur varies, (although constant as

regards the impulses of any one signal) the receiver has to be provided with a device for regulating the phase position of the selecting mechanism relatively to the start-stop mechanism.

At the first release of the armature 148 after the start impulse, the start-stop mechanism couples the shaft 118 to the sleeve 128 through the clutch wheels 116 and 130 for half a revolution. This sleeve 129 (Fig. 14) is coupled to the sleeve 129 of the selector gear by the dogs 135 on the flange 136 which engage in the oblique grooves 134 at the forward end of the sleeve 128. The flange 136 is fixed to the sliding sleeve 137 which is guided in the longitudinal slot 138 in the sleeve 129. The sliding sleeve 137 is formed with a circumferential groove in which half rings 397 are housed. The ring 397 is held by means of the nut 139 on the tubular screw threaded extension 140 of the fixed drum 141. The nut 139 has a milled head 142 with which engages resiliently a blade 143 mounted on the frame 145 (Fig. 2).

The ring 136 is displaced by rotation of the nut 139 which can be effected when the blade 143 is lifted. This rotation brings the dogs 135 against the walls of the oblique slot 134 which have a definite position in the normal position of the start-stop mechanism and the grooves 138 in the sleeve 129 are caused to take up a new position relatively to the start-stop mechanism. The distributor arm 152 and the cam disc 160 30 are thus rotated relatively to the sleeve 128 of the start-stop mechanism.

The setting nut 139 can be provided with markings to determine the phase position of the selecting mechanism relative to the start-stop 35 mechanism.

The arm 152 and its lugs 151 and 156 slide over the rising parts of the cams 149 on the fixed drum 141 and come up against the lugs 231 of the levers 157 controlling the testing levers 40 158 at particular instants of time during the received signal impulses, according to the relative phase positions assumed by the selecting mechanism and the start-stop mechanism. Also, by means of the cams 163 on the disc 168 (Fig. 7) the armature 148 is pressed towards the pole 165 at the appropriate most favourable instant of time. In this way, the armature, the position of which determines the position of the drum 153 and the arm 152, is controlled with certainty by the magnet even with strongly distorted impulses. The most favourable phase position, which may vary quickly particularly with open line telegraph operation can be set and corrected during operation.

55 A printing device translates the position given to the type wheel shaft 122 by the selecting mechanism. If the shaft is in a position associated with letters or signals, printing will be effected; if in a position associated with switching steps, printing will be prevented.

This printing mechanism is controlled by the cam discs II—V on the carrier 264 (Fig. 15) which is mounted on the shaft 107. The lever devices cooperating with these cams control further levers (not illustrated) some of which cooperate with the cam discs 127 on the type drum 126 and others of which effect the release and return of the printing hammer 227.

The sleeve 261 by means of which the part 262, 70 (Figs. 15 and 16) of the clutch 260, 262 is fixed on the shaft 107 carries the sliding half 260 of the clutch. The part 260 is pressed towards the part 262 by a helical spring 266 which abuts against the carrier 264. The carrier 264 is freely 75

mounted on the end of the shaft 107 and rotates with the part 260.

The cam discs II—V can be carried round through one-third of a revolution of the shaft 107 by means of the clutch 260, 262.

The clutch 260, 262 is controlled by a pawl 241 pivoted at 255. This pawl has two claws 257 and 258 (Fig. 16) which cooperate with the diamond shaped projections 259 on the part 260 of the clutch. A spring 242, (Fig. 18) tends to keep the pawl 241 out of engagement with the projections 259.

The pawl 241 is pivoted by a rod 240 hinged to it and pressed by the spring 242 against the front of two arms 249 and 250 pivotally mounted on a common pin 248 which is arranged in line with the rod 240.

The arms 249 and 250 are pressed together by a spring 251 and can be swung about their hinge 248 by means of a pin 252 on a T-shaped member 254 also pivotally mounted on the pin 248. The branches of the T-shaped member are engaged by control levers 246 and 247. The control levers 246 and 247 can be acted on by the arms 208 and 208' (Figs. 9, 10 and 18) which are adjustably fixed to the testing levers 158V and 158I.

The arrangement controlled by the rods 246 and 247 operates as follows:—

When the testing levers of the set B (Figs. 9, 10 and 18) are removed from the code discs and the lever 158I' is pivoted clockwise, the arm 208' moves away from the left hand end of the rod 247 (Figs. 15, 17 and 18). At the same time, the testing lever 158V of the set A is placed on its code disc and remains there until the ends 203 of the testing levers of this set A find it possible to engage in the discs in the so called testing position. As long as the lever 158V is not fully engaged, the arm 208 has no effective influence on the right hand end of the rod 246. When, however, the testing position is reached, (Fig. 18) the rod 246 is pressed towards the right by the arm 208 acting under the influence of the pull of the spring 206 which also accelerates the engagement in the code discs of the set of testing levers A. The T-shaped lever 248 carrying the pin 252 is thereby pivoted clockwise as is therefore the lever 249 against the front face of which the rod 248 has, up till now, been pressed. The lever 250 is also caused to turn by the spring 251.

The rod 240 moves towards the right under the pull of the spring 242 and arrives in a position between the levers 249 and 250 and thus prevents the full pivotal movement of the arm 250 which remains in an intermediate position, (Figure 17) and causes the spring 251 to be extended.

It is only when, later on, the rod 240 is temporarily pressed towards the left that the arm 250 will move from its intermediate position under the influence of the tensioned spring 252 and abut against the arm 249 which has been swung into its extreme position (Fig. 19). The rod 240 now abuts against the front of the pivoted arm 250. It is only when the set of testing levers A has been made inoperative and the levers of the set B are placed on the code discs and have engaged therein and the pivoted levers 249, 250 are swung counter-clockwise, that the rod 240 and with it the pawl 241 are released.

There are three diamond shaped projections 259 spaced at equal intervals on the circumference of the clutch member 260 (Fig. 16). By means of these projections, the cam discs II—V are released for the duration of one-third of a revolution of the shaft 109. The cam discs II—V

have three corresponding humps uniformly distributed over their circumference.

The clutch member 260 is permanently under the pressure of the helical spring 266 so that when released by the pawl 241, it is moved towards the wheel 262 for the purpose of clutching the cam discs II—V to the shaft 107.

When the pawl 241 is disengaged, the clutch member 260 is free for axial and angular movement (Fig. 17). Shortly before the end of $\frac{1}{3}$ of a revolution, the sloping face of the next projection 259 abuts against a corresponding sloping face on the arm 257 of the pawl 241 which has been again brought into action in the meantime. Consequently, the clutch member 260 is displaced against the action of the spring 266 and, as the projection 259 abuts against the head of the arm 258 of the pawl 241 is held after exactly $\frac{1}{3}$ of a revolution. The cam disc II, shortly after the beginning of the rotation of the carrier 264 presses on the finger 268 of the pawl 241 and, on further rotation, swings it against the action of the spring 242 into the locking position. In this way, the rod 240 is again attracted to the left and then abuts on the front face of one of the levers 249 and 250 of the escapement mechanism. The pawl 241 is thus again held in its locked position.

During the rotation of the cam discs II—V for one-third of a revolution, various levers are actuated by these cam discs so as to influence the printing hammer for striking the type to which the type wheel has been set or to prevent printing and effect desired switching operations. The cams of the cam discs II—V also serve for the displacement of the paper to be printed and of the ink ribbon. This is not illustrated in detail as it is of no importance as regards the invention.

We claim:—

1. Type printing apparatus comprising a selecting device for determining a type according to received code current impulses of the Baudot type, said selecting device comprising a type wheel, a set of selecting discs connected to said type wheel, means for rotating said selecting discs and said type wheel, a set of testing members adapted to control said selecting discs, a setting device for setting said testing members relatively to said selecting discs, means for rotating said setting device, means for setting said setting device during its rotation, a magnet adapted to be influenced by said code current impulses and provided with an armature adapted to influence the setting of said setting device, and means acted upon by said setting device during its rotation whereby to set said testing members successively under the influence of said means for rotating said setting device and in dependence upon said armature.

2. Apparatus as claimed in claim 1 in which said means for setting said setting device during its rotation comprise a stationary disc provided with cams on its circumference adapted to displace said setting device axially during its rotation.

3. Apparatus as claimed in claim 1, in which said means for setting said setting device during its rotation comprise a fixed disc provided with a ring of cams arranged in pairs diametrically opposite each other and adapted to act simultaneously on said setting device to displace it axially.

4. Type printing apparatus comprising a selecting device for determining a type in accord-

ance with received code current impulses of the Baudot type, said selecting device comprising a type wheel, a set of selecting discs connected to said type wheel, means for rotating said selecting discs and said type wheel, a set of testing members adapted to control said selecting discs, a rotary setting device for setting said testing members relatively to said selecting discs, a magnet adapted to be influenced by said code current impulses and having an armature adapted to influence said setting device, a cam disc clutched to said setting device, means acted upon successively by the cams of said cam disc whereby to displace said armature intermittently during rotation of said disc towards the pole of said magnet, a stationary cam disc, means acted upon successively by the cams of said stationary disc whereby to intermittently displace said setting device axially during its rotation, a spring acting on said setting device and opposing said axial displacement of said setting device; said setting device, the cams of said movable cam disc and the cams of said stationary cam disc being so arranged that the cams of the stationary cam disc release said setting device for axial displacement under the action of said spring, at the earliest, at the same time as that at which the cams of said movable cam disc release said armature of said magnet.

5. Type printing apparatus comprising a selecting device for determining a type in accordance with received code current impulses of the Baudot type, said selecting device comprising a type wheel, a shaft for said type wheel, two selecting discs arranged one beside the other on said shaft and connected to said type wheel, means for rotating said selecting discs and said type wheel, a set of testing members adapted to control said selecting discs and arranged for displacement parallel to the shaft of said selecting discs, a setting device for setting said testing members relatively to said selecting discs, a shaft for said setting device, said setting device being arranged for axial displacement on its shaft, means for rotating said setting device, stationary means for periodical axial displacement of said setting device during its rotation, a spring acting on said setting device in opposition to said means for axially displacing it, a magnet adapted to be influenced by said code current impulses and provided with an armature adapted to hold said setting device in its axially displaced position against the action of said spring, means acted upon by said setting device in its axially displaced position whereby to set said testing members successively out of their normal position under the influence of said means provided for its rotation, a rotary resetting device for said testing members set in rotation by said means for rotating said setting device and disposed in advance of said setting device in the direction of rotation of the latter, and means acted upon by said resetting device during its rotation whereby to return said testing members successively into their normal position.

6. Type printing apparatus comprising a selecting device for determining a type in accordance with received code current impulses of the Baudot type, said selecting device comprising a type wheel, a shaft for said type wheel, two selecting discs arranged one behind the other on said shaft and connected to said type wheel, means for rotating said selecting discs and said type wheel, a shaft parallel to the shaft of the

selecting discs, a set of testing members on said last mentioned shaft adapted to control said selecting discs and arranged for axial and rotary displacement on said shaft, projections on said testing members whereby each of them is supported by the testing member below it in each of its axial positions, a setting device for axially displacing said testing members, means for rotating said testing members about their axes, a magnet adapted to be influenced by said code current impulses and having a projection adapted to influence said setting device.

7. Apparatus as claimed in claim 6, in which said selecting discs are provided on their circumference with grooves and humps and said testing members are provided with noses adapted on rotation of said testing members to be brought to lie on the circumference of said selecting discs and, on rotation of said discs to engage in said grooves in said selecting discs whereby to stop directly rotation of said selecting discs.

8. Apparatus as claimed in claim 6, comprising also a spring acting on said testing members and tending to rotate them as a whole about their axes, said means for rotating said testing members being constructed as a rotary disc comprising a controlling cam and a lever controlled by said controlling cam acting on said testing members for holding said testing members against rotation by said spring and for allowing such rotation.

9. Type printing apparatus comprising a selecting device for determining a type in accordance with received code current impulses of the Baudot type, said selecting device comprising a selecting wheel, two sets of type discs connected to said selecting wheel, each of said two sets of type discs being of similar construction and being displaced relatively to each other through 180°, means for rotating said sets of selecting discs and said type wheel, two sets of testing members, one set of selecting discs being associated with each of said sets of testing members, means controlled by each of said sets of testing members for controlling the associated set of selecting members, the testing members of each set having axes of rotation parallel to the axis of rotation of said selecting discs, the testing members of each set being provided with projections for mutual support of the testing members of a set, a spring for each set of testing members striving to rotate all the testing members of one set as a whole about their axes, said testing members being provided with noses adapted, on said testing members being rotated about their axes, to be brought to lie on the circumference of said selecting discs, a control lever for each of said sets of testing members for preventing and for allowing movement of each set of testing members under the influence of said spring, a rotary disc provided with a control cam for controlling said levers in such a way that at any time there is only one set of testing members which is rotated under the influence of its spring, a rotary setting device, a magnet adapted to be influenced by said code current impulses, said magnet being provided with an armature adapted to influence said setting device, and means acted upon by said setting device during its rotation whereby to displace the testing members of said two sets axially relatively to said selecting discs.

10. Type printing apparatus for printing type characters comprising a selecting device for determining a type in accordance with received

code current impulses of the Baudot type, said selecting device comprising a type wheel, a set of selecting discs connected to said type wheel, means for rotating said selecting discs and said type wheel, a set of testing members adapted to influence said selecting discs, said testing members being displaceable relatively to said selecting discs, a rotary setting device for said testing members, a magnet adapted to be influenced by said code current impulses, said magnet being provided with an armature adapted to influence said setting device, means for rotating said setting device through one revolution, said last mentioned means being controlled by the armature of said magnet and means for rotating said setting device relatively to said means for rotating it through one revolution.

11. Type printing apparatus comprising a set of code discs, a type wheel, means for rotating said code discs and said type wheel in unison, a magnet adapted to receive a train of current impulses of the Baudot type, a set of testing members mounted for independent displacement, means for arresting said code discs and said type wheel in various positions dependent upon the relative setting of said testing members, a source of power other than said magnet and means under the influence of said source of power for effecting said relative setting of said testing members in accordance with the current impulses received by said magnet.

12. Type printing apparatus comprising a selecting device for determining a type in accordance with received code current impulses of the Baudot type, said selecting device comprising a type wheel, a set of selecting discs connected to said type wheel, a set of testing members adapted to control said selecting discs, a rotary member mounted for axial displacement during its rotation, means for rotating said rotary member, stationary means for displacing said rotary member axially during its rotation in one direction as said member passes through particular angular positions, a spring urging said rotary member axially in the other direction in all angular positions of said member, a magnet operated by said code current impulses and having an armature adapted to hold said rotary member against displacement by said spring, and means acted upon by said rotary member during its rotation whereby to set said testing member selectively in accordance with the axial displacements of said rotary member.

13. Type printing apparatus comprising a selecting device for determining a type in accordance with received code current impulses of the Baudot type, said selecting device comprising a type wheel, a set of selecting discs connected to said type wheel, means for rotating said selecting discs and said type wheel, a set of testing members adapted to control said type discs, a setting device for setting said testing members relatively to said selecting discs comprising a rotary arm, a ring adapted to rotate with said arm, means for

rotating said arm, a stationary disc provided with cams adapted to displace said arm axially during its rotation, a spring constantly urging said arm towards said stationary disc, a stop adapted to engage between said ring and said disc whereby to hold said arm against displacement by said spring, electromagnetically controlled means adapted, under the influence of said code current impulses, to determine the engagement of said stop between said ring and said stationary disc and means acted upon by said arm during its rotation whereby to set said testing members selectively in accordance with the axial displacements of said arm.

14. Apparatus as claimed in claim 13, in which said electro-magnetic means comprise a magnet having an armature to which said stop is yieldingly connected.

15. Apparatus as claimed in claim 12, comprising also a cam disc adapted to move with said rotary member, the cams of said cam disc being adapted to press said armature in a preparatory manner towards the pole of the magnet.

16. Apparatus as claimed in claim 12, comprising also a rotary cam disc adapted to be rotated together with said rotary member and having a plurality of cams adapted to press said armature towards the pole of said magnet periodically during the reception of said code current impulses, said cams being arranged so as to act successively on said armature and being made of increasing lengths.

17. Apparatus for printing types selected in accordance with received current impulse signal trains of the Baudot type, comprising a type wheel, two sets of selecting discs, means for rotating said type wheel and said selecting discs in unison, two sets of testing members associated one with one and the other with the other of said sets of selecting discs, a magnet actuated by said received current impulse signal trains, means controlled by said magnet on receipt of successive trains for alternately setting the testing members of said sets of testing members into relative positions corresponding to the received train, means for bringing said sets of testing members individually with their testing members in said relatively displaced positions into contact with the associated selecting discs whereby to cause rotation of said discs to be arrested when said discs assume an angular position determining the selection of a type on said wheel corresponding to the received train, and a printing device comprising means for producing an impression from said selected type, rotary means controlling said type impressing means, a clutch controlling the rotation of said rotary means and an escapement mechanism controlling said clutch, said escapement mechanism being controlled by said trains of testing members.

MAX AMANN.
